[57] CLAIM

The ornamental design for an orthodontic bracket, as shown and described.

DESCRIPTION

FIG. 1 is a front perspective view of an orthodontic bracket showing my new design;

FIG. 2 is a rear perspective view thereof;

FIG. 3 is a top plan view thereof;

FIG. 4 is a front elevational view thereof;

FIG. 5 is a left side elevational view thereof, the right side being a mirror image;

FIG. 6 is a rear elevational view thereof;

FIG. 7 is a bottom plan view thereof;

FIG. 8 is a front perspective view of a second embodiment thereof, the only difference residing in the circular indentation on the front elevation;

FIG. 9 is a top plan view of a third embodiment thereof;

FIG. 10 is a front elevational view of the embodiment of FIG. 9;

FIG. 11 is a left side elevational view of the embodiment of FIG. 9, the right side being a mirror image;

FIG. 12 is a rear elevational view of the embodiment of FIG. 9;

FIG. 13 is a bottom plan view of the embodiment of FIG. 9; and

FIG. 14 is a front perspective view of a fourth embodiment thereof, the only difference between the embodiment of FIG. 9 residing in the circular indentation on the front elevation.
